CLAIM

I, Mathew Inskeep, claim the ornamental design for a battery charger, as shown and described.

DESCRIPTION

FIG. 1 is a top perspective view of a battery charger showing my new design.

FIG. 2 is a bottom perspective view thereof.

FIG. 3 is a top view thereof.

FIG. 4 is a bottom view thereof.

FIG. 5 is a left side view thereof.

FIG. 6 is a right side view thereof.

FIG. 7 is a front view thereof.

FIG. 8 is a back view thereof.

FIG. 9 is a front view with cables unhinged power outlet exposed; and,

FIG. 10 is a back view with cables unhinged and plug exposed.
